UNITED STATES PATENT OFFICE.

JOHN S. FREY, OF GLENDALE STATION, NEW YORK, ASSIGNOR TO SILVER & COMPANY, OF BROOKLYN, NEW YORK, A CORPORATION OF NEW YORK.

OIL-STOVE BURNER-CUP.

SPECIFICATION forming part of Letters Patent No. 739,486, dated September 22, 1903.

Application filed May 19, 1903. Serial No. 157,858. (No model.)

To all whom it may concern:

Be it known that I, JOHN S. FREY, a citizen of the United States of America, and a resident of Glendale Station, Queens county, in 5 the State of New York, have invented a new and useful Improvement in Oil-Stove Burner-Cups, of which the following is a specification.

This invention relates to what are known as "blue-flame" oil-stoves of that species in 10 which an annular burner-cup containing a short incombustible wick or lighting-ring is combined with superposed combustion-tubes concentric with the burner-cup and with each other and adapted to be removed from the 15 burner-cup and replaced thereon when the oil is ignited. Such combustion-tubes are commonly held concentrically within an opaque drum of sheet metal, and the latter is provided with a cold handle by means of 20 which the drum and combustion-tubes as one part are conveniently handled. As the drum conceals the combustion-tubes from view, some means to facilitate locating them upon their seats, forming part of the burner-cup, 25 is desirable. Various devices for this purpose have been proposed. I have discovered that by a very simple change in the construction of the burner-cup itself the ordinary combustion-tubes may be seated with the utmost facility, even when they are handled by 30 an inexperienced person.

The present invention consists in a burner-cup constructed as and for the purpose above indicated and in its combination with superposed combustion-tubes held within an 35 opaque drum.

A sheet of drawings accompanies this specification as part thereof.

Figure 1 is a sectional elevation showing 40 the improved burner-cup in section and illustrating by full and dotted lines the operation of seating the combustion-tubes on the burner-cup. Fig. 2 is a top view of the burner-cup.

Like reference letters and numbers refer to like parts in both figures.

The improved annular burner-cup (shown at A in Fig. 1 and segregated by Fig. 2) is or may be of any known or improved construction, comprising concentric horizontal shoul-

ders or seats 1 and 2 for the respective combustion-tubes *a* and *b* of a blue-flame oil-stove, concentric walls or curbs 3 and 4 at the perimeter and inner circumference of the burner-cup, respectively, and an annular depression or trough 5 midway between said curbs to hold the short incombustible wick or lighting-ring *B*. 55

The outer curb 3 is made higher than the inner curb 4, as shown in Fig. 1, and the latter, 4, terminates in an inwardly-projecting horizontal flange 6, forming a level surface upon which the lower edges of the combustion-tubes *a* and *b* (either or both) may slide from any position in which they may strike 60 the same when they are lowered upon the burner-cup to their positions of rest upon their seats 1 and 2, as illustrated by full and dotted lines in Fig. 1.

The burner-cup *A* is preferably and conveniently supported and supplied with oil by a Y-shaped coupling-piece 7, permanently attached to the burner as part thereof and in communication with said annular trough 5 at bottom, and a perforated diaphragm *C* is held 75 in place within the burner-cup beneath the inner combustion-tube seat 2.

The combustion-tubes *a* and *b* are centrally supported within a sheet-metal drum *D*, which may be of any known or improved shape and 80 proportions and is provided with the customary cold handle *c*.

The width of the level-surface-forming flange 6 may be increased to any desired extent that will not interfere with the function 85 of the central air-passage 8, and other like modifications will suggest themselves to those skilled in the art.

Having thus described said improvement, I claim as my invention and desire to patent 90 under this specification—

1. An annular burner-cup, for a blue-flame oil-stove, having concentric horizontal seat portions, a curb extending around the perimeter of the burner at the outer extremity of 95 the outermost of said seat portions; a curb of less height than the curb first named, extending around the inner circumference of the burner, and a level-surface-forming horizontal flange projecting inwardly from the up- 100

per extremity of said inner curb, substantially as hereinbefore specified.

2. In combination with a pair of combustion-tubes supported within an opaque drum 5 and movable therewith, an annular burner-cup having horizontal seat portions upon which the lower edges of said combustion-tubes rest when in place, a curb extending around the perimeter of the burner-cup and 10 surrounding the outer tube when said tubes are in place, a curb of less height than the curb first named extending around the inner

circumference of the burner-cup, and a level-surface-forming horizontal flange projecting inwardly from the upper extremity of the 15 curb last named, whereby said combustion-tubes are adapted to slide into place upon their respective seats, substantially as hereinbefore specified.

JOHN S. FREY.
